(57) **CLAIM**

The ornamental design for an electric bicycle, as shown and described.

DESCRIPTION

The file of this patent contains at least one drawing/photograph executed in color. Copied of this patent with color drawing(s)/photograph(s) will be provided by the office upon request and payment of the necessary fee.

FIG. 1 is a perspective view of the electric bicycle showing my new design;

FIG. 2 is another perspective view thereof;

FIG. 3 is a front elevational view thereof;

FIG. 4 is a rear elevational view thereof;

FIG. 5 is a left side elevational view thereof; and,

FIG. 6 is a right side elevational view thereof.
